UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

CONTROLLER.

SPECIFICATION forming part of Letters Patent No. 755,744, dated March 29, 1904.

Application filed October 1, 1902. Serial No. 125,575. (No model.)

To all whom it may concern:

Be it known that I, FRANK E. CASE, a citizen of the United States, residing at Schenectady, county of Schenectady, State of New York, 5 have invented certain new and useful Improvements in Controllers, of which the following is a specification.

My invention relates to improvements in electric controllers, and especially to that class 10 of controllers used upon electric-railway vehicles to control the circuits of the motors thereon.

The object of my invention is to provide a cheap, simple, and effective arc-extinguishing 15 device to disrupt and suppress the arcs formed between the segments and contact-fingers of the controller employed in connection with the motors and resistances associated therewith.

The invention consists in certain features of 20 construction and combination of parts, as will be hereinafter described, and pointed out in the claims.

In the accompanying drawings, Figure 1 is 25 a view in elevation of a controller constructed according to my invention, the front casing of the controller being removed. Fig. 2 is a side elevation, partly in section, of the controller shown in Fig. 1. Fig. 3 is a section on the line 3 3, Fig. 1; and Fig. 4 is a section on the 30 line 4 4, Fig. 2, to show more clearly the path followed by the magnetic flux produced in the core of the blow-out coil.

Referring now to the drawings, C represents a controller-casing, the back C' of which 35 is made of magnetic material. The cover or door of the casing is represented by C², and the cap-plate by T. Within the casing C is mounted on the shaft S, in a manner to be hereinafter described, the controller drum or 40 cylinder D, which carries the projecting contact-segments F. These segments are adapted to engage with the relatively fixed contact-fingers f', located on opposite sides of the controller drum or cylinder and mounted on the 45 insulating-blocks H in a manner well known in controller construction. The leads which are connected electrically with these fingers are soldered, brazed, or otherwise connected

to the terminals f². The controller cylinder or drum is rotated by means of a handle (not shown) adapted to be attached to the end of the shaft S, which projects through the cap-plate T of the casing A. The notched ring or sector r is adapted to hold the controller-handle in its various operative positions in the 55 customary manner. Also mounted within the casing C is a reversing-switch R, comprising the rotatable member h, carrying the contact-plates and the relatively fixed contact-fingers g, which are adapted to engage with the contact-plates t as the member h is rotated. The contact-fingers are mounted on the insulating-blocks g'. The rotatable member h is operated by means of a handle adapted to be attached to the upper end of the vertical shaft S', which 60 extends through the cap-plate of the casing. The said shaft S' carries at its lower end a crank v, which is connected to the counter-shaft S² by means of a link mechanism, (not shown,) and the said counter-shaft is opera- 70 tively connected to the rotatable member h of the reverse-switch. The leads of the relatively fixed contact-fingers g of the reversing-switch are electrically connected to said fingers at the terminals g².

Mounted on the pivots e on either side of the main controller cylinder or drum D are the arms E, which are made of magnetic material and carry at their outer ends a series of insulating-pieces p, which are adapted to 80 project between the outwardly - projecting contact-segments F on the controller-drum. These insulating-pieces are recessed and are adapted to embrace the contact-fingers f' in such a manner as to form arc-deflectors which 85 guide the arc which forms between the contact-fingers and the segments on the drum as said arc is disrupted by the action of the magnetic flux, in the path of which the contact-fingers are located. The manner in which 90 said magnetic flux is produced and the path followed by the same will be hereinafter described. The insulating separating-strips or arc-deflectors p are mounted on the insulating-strip k, fastened directly to the arms E, 95 and the distance between separate strips is

maintained constant by means of the vertical strip E', which is fastened to the tips of said insulating-pieces.

The controller cylinder or drum D is built up in the following manner: Rigidly mounted on the shaft S are collars d², which are formed with radially-projecting fingers d³, as shown in dotted lines in Figs. 3 and 4. Concentrically arranged with respect to said collars d² and held in place thereon by means of the insulating material d⁵ are collars or rings d', having inwardly and radially projecting fingers d³, which when the collars d' and d² are assembled to form a single disk alternate with the outwardly and radially projecting fingers d⁴. The inner ends of the fingers d³ of the ring or collar d' project within the circle circumscribed about the shaft S through the outer tips of the radially-projecting fingers d⁴.

20 The cylindrical part d of the drum D, on which the contact-segments F are mounted, is bolted to the collars d' in such a manner as is shown in Fig. 2 of the drawings.

Such a construction as hereinbefore described prevents the shearing which would be liable to take place between the cylinder d and the collars d² due to the inertia of the heavy moving parts on the drum. A cylinder, of insulating material, placed between the shaft S and the cylinder d could not possibly prevent this relative movement or shearing action between the said drum and the collars d². Since it is absolutely necessary to insulate the shaft S from the cylindrical part of the drum which carries the contact-segments, it can readily be seen that for the large controllers in which the present invention is adapted to be used such a construction as above described is quite necessary.

25 40 Between the controller-cylinder and the reversing-switch is an interlocking device, which operates to prevent the reversing-switch from being moved while the controller-cylinder is in any position other than its "off" position. A 45 notched sector (represented by z) is carried by the main shaft S, and mechanism (not shown) operatively connected with the reversing-switch is adapted to coact therewith. The controller cylinder or drum D is made up in 50 separate sections insulated from each other, which is a construction well known in the art. I and I' represent insulating-disks located within the casing at the ends of the controller-shaft S.

55 The projection C³, which is made of magnetic material and is formed integral with the back C' of the controller, constitutes the core of an electromagnet which furnishes the required flux for the magnetic blow-out. The 60 coil A is wound on the core C³, as shown in the figures of the drawings, and is adapted to be connected in the circuit in which the controller is located. This coil A constitutes the means whereby the core is magnetized. The 65 projection C³ lies adjacent to the cylinder or

drum D and has formed on its outer face lugs f, which are adapted to project between the contact-segments F of the controller-cylinder and extend very close to the cylindrical surface. As the cylinder D is made of magnetic material and forms part of the path followed by the magnetic flux produced in the core C³, the most important function of the projections or lugs f is to reduce the air-gap between the core C³ and the cylinder D. The 70 path of the magnetic flux emanating from the core C³ is indicated in Fig. 4 by the dotted lines x and may be traced as follows: from core C³, through the cylindrical part d of the cylinder or drum D, across the gap in which the contact-fingers f' are located, through the pivoted arms E and the back of the controller-casing C to the core C³. A strong magnetic blow-out field is thereby produced at the points of contact of a plurality of rows of contact-fingers with the contact-segments of the controller-cylinder by means of a single magnetizing-coil. In order to prevent the possibility of short-circuit due to contact between the drum D or the segments thereon 80 and the core C³ or its lugs f, I have provided an insulating-covering B for said core and lugs.

I have herein shown and described a preferred form of my invention; but I do not 90 wish to be limited to the specific device shown, as many modifications and changes in the relative location of parts may be made without departing from the spirit and scope of my invention.

100 What I claim as new, and desire to secure by Letters Patent of the United States, is—

1. In a controller, a drum or cylinder having a plurality of projecting contact-segments on its periphery, a single magnet-core contiguous to said drum having a plurality of projections or lugs which extend between and are adapted to embrace said segments, a single coil for magnetizing said core, and contact-fingers adapted to engage said segments in the path of the fluxes produced in said core by said magnetizing-coil.

2. In a controller, a drum of magnetic material provided with a plurality of projecting contact-segments, a magnetic core arranged adjacent to said drum and provided with a plurality of lugs projecting between said contact-segments into proximity with said drum, a coil for magnetizing said core to produce a magnetic flux which passes through said drum, and a row of contact-fingers located in the path of the magnetic flux produced by said core and adapted to engage said contact-segments.

3. In a controller, a drum of magnetic material, a magnet-core arranged adjacent to said drum, a single coil for magnetizing said core to produce a magnetic flux which passes through said drum, and a plurality of rows of contact-fingers adapted to engage with the contacts on said drum, said fingers being arranged in

the path of the magnetic flux produced in said core.

4. In a controller, a rotatable drum or cylinder of magnetic material, a fixed magnet-
5 core arranged adjacent to said drum, means for magnetizing said core, and a row of contact-fingers arranged on each side of said core in the path of the magnetic flux produced in said core, said fingers being adapted to engage
10 with the contact-segments on the periphery of said drum.

5. In a controller, a drum having projecting segments on its periphery, a magnetic core having projecting lugs arranged adjacent to
15 said drum, the said lugs lying between the projecting segments of said drum or cylinder, means for magnetizing said core, and a row of contact-fingers arranged on each side of said core in the path of the magnetic flux produced in said core, said fingers being adapted
20 to engage with the contact-segments of the periphery of said drum, and an insulating-covering for said core and projecting lugs.

ed to engage with the contact-segments on the periphery of said drum.

6. In a controller, a drum having projecting segments on its periphery, a magnetic core having projecting lugs arranged adjacent to
25 said drum, the said lugs lying between the projecting segments of said drum or cylinder, means for magnetizing said core, a row of contact-fingers arranged on each side of said core in the path of the magnetic flux produced in said core, said fingers being adapted
30 to engage with the contact-segments of the periphery of said drum, and an insulating-covering for said core and projecting lugs.

In witness whereof I have hereunto set my 35
hand this 30th day of September, 1902.

FRANK E. CASE.
